TAPE CLAMP

Francesco Collura, New York, N.Y., and Carl R. Sellen,
Paramus, N.J., assignors to Keuffel & Esser Company,
Hoboken, N.J., a corporation of New Jersey

Filed Jan. 21, 1966, Ser. No. 723

Term of patent 14 years

(Cl. D54—13)

FIG. 1

FIG. 1 is a front and side perspective view of a tape clamp, showing the new design.

FIG. 2 is a perspective view from the opposite side showing the rear and opposite side of the tape clamp.

FIG. 3 is a side elevation of the tape clamp.

The fragmentary broken line showing of the tape in FIGURES 1 and 2 is depicted for illustrative purposes only.

We claim:

The ornamental design for a tape clamp as shown and described.
